WITNESS:

UNITED STATES PATENT OFFICE

DALE E. FOLTZ, OF GRANVILLE, PENNSYLVANIA

TOY HORSE

Application filed April 14, 1928. Serial No. 269,988.

The present invention relates to the art of toys and particularly to an improved toy horse, more especially to the manually propelled type, hence including supporting 5 wheels, a single one in front and two at the rear.

The present invention has for its purpose to provide, in a toy of this kind a supporting axle at the rear for the support of a pair of 10 wheels, which are mounted on the axle eccentrically, that is oppositely eccentric, whereby the rear of the body of the toy horse may be given an up and down movement, and a side wobbling movement, in order to give a substantially true representation of the movement of a horse when trotting.

Another purpose is to provide a conventional type of steering column with steering handles and a fork for the front wheel, the 20 column being mounted in the body of the toy, so that the front wheel may swivel to the right or to the left, whereby the toy may be steered in either direction.

It is to be understood that the particulars 25 herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a view in side elevation of the 35 improved vibrating toy horse constructed in accordance with the invention.

Figure 2 is a rear view showing the tilt of the body of the horse.

Referring to the drawing, 1 identifies the body of a toy horse, having a head 2 and terminating at the rear in a seat 3, and swiveled on an incline through the body 1 is a steering column or post 4 which passes through a conventional type of ball bearings 5 adjacent the top and bottom of the body of the horse. The steering column where it passes through the body of the toy is cylindrically enlarged, and thereby causing shoulders 6^a and 6^b to be formed at the opposite ends of the enlarge-

ment. Suitable bearing sleeves 6^c and 6^d are fixed into the opposite upper and lower portions of the body and cooperating with the ball bearings 5 (which in turn cooperate with the shoulders) to hold the column 55 against axial movement. This steering column has its upper end provided with handle bars 6 and terminates at its lower end in forks 7. The handle bars may be detachable from the steering column or post at 4^a in 60 order to permit the column to be inserted through the body of the toy. Journaled in the forks 7 is the usual crank axle 8 having crank arms and pedals 9, in order to impart movement to the single wheel 10, which is 65 journaled upon the axle 8 so that the toy horse may be propelled as desired, and through the medium of the handle bars the single front wheel may be turned either in 70 the direction of the right or left for steering the toy.

A depending U-shaped frame 11 is secured at 12 to the rear portion of the body of the toy, and journaled in bearings of the arms of said frame is a rear axle 13, on which the rear 75 supporting wheels 14 are mounted. The wheels 14 are oppositely eccentric. For instance the one on the right as shown in Figure 2 engages with the axle at a point below the center of the wheel, while the one of the left engages with the axle above the center of the wheel, so that when the toy is propelled by the pedals, the rear axle oscillates, the right end moving up and down, while the left moves down and up, these movements being 80 alternately and therefore imparting a rocking movement to the body of the toy, that is a rocking movement laterally as well as up and down movement, therefore imparting to the toy a movement substantially in true representations of the movement of the body of 85 a horse when trotting.

Said U-shaped frame is provided with a transverse brace 15, thereby preventing the arms of the frame from spreading.

The invention having been set forth, what is claimed is:

A toy horse comprising a body provided with an inclined bore formed on an incline through the body, a forward front steering 90

column mounted in said bore, said steering column where it passes through the bore being enlarged, said enlargement causing shoulders to be formed adjacent the opposite ends of the enlargement, and means fixed in the upper and lower parts of the body and cooperating with the shoulders to hold the steering column against the axial movement, the upper end of the steering column having handle bars, and a steering wheel including propelling means operatively mounted at the lower end of the steering column, a frame secured to the rear end of the body and inclined downwardly and having an axle in bearings of its lower end, and a pair of rear supporting wheels mounted on the ends of the axle and fixed oppositely eccentric with relation to the axle whereby up and down swaying movements may be imparted to the body.

10   20   In testimony whereof he affixes his signature.

DALE E. FOLTZ.
